US0D1011294S

(12) **United States Design Patent** (10) **Patent No.:** **US D1,011,294 S**
(45) **Date of Patent:** **** Jan. 16, 2024**

(54) **CAPACITOR**

(71) Applicant: **Samwha Electric Co., Ltd.**,
Cheongju-si (KR)

(72) Inventors: **Jong On Park**, Cheongju-si (KR); **Tae Yun Kim**, Sejong-si (KR); **Eun Kyun Joo**, Cheongju-si (KR); **Young Jin Kwon**, Cheongju-si (KR); **Won Seop Song**, Cheongju-si (KR)

(73) Assignee: **Samwha Electric Co., Ltd.**,
Cheongju-si (KR)

(**) Term: **15 Years**

(21) Appl. No.: **29/796,182**

(22) Filed: **Jun. 23, 2021**

(51) LOC (14) Cl. **13-03**

(52) U.S. Cl.

USPC **D13/125**

(58) **Field of Classification Search**

USPC D13/123-132, 154, 199, 184
CPC H01G 4/224; H01G 4/28; H01G 4/385;
H01G 4/40; H01G 4/232

See application file for complete search history.

(57) **CLAIM**

The ornamental design for a capacitor, as shown and described.

DESCRIPTION

FIG. 1 is a perspective view of a capacitor showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

1 Claim, 5 Drawing Sheets
